(57) **CLAIM**

The ornamental design for a razor stand, as shown and described.

DESCRIPTION

FIG. 1 is a front perspective view of the razor stand in an assembled state, comprising a cover assembled to a base; FIG. 2 is a right side view of the razor stand in an assembled state; FIG. 3 is a rear view of the razor stand in an assembled state; FIG. 4 is a bottom view of the razor stand in an assembled state; FIG. 5 is a bottom rear perspective view of the razor stand in an assembled state; FIG. 6 is a right side view of the base alone; FIG. 7 is a top view of the base alone; FIG. 8 is a front view of the base alone; FIG. 9 is a front perspective view of the base alone; and, FIG. 10 is an exploded front perspective view of the razor stand, in which the cover is separated from the base. The broken lines shown in the drawings illustrate portions of the razor stand that form no part of the claimed design.
